UNITED STATES PATENT OFFICE.

JOHN WALDHEIM, OF ELIZABETH, NEW JERSEY, ASSIGNOR TO UNDERWOOD TYPE-WRITER COMPANY, OF NEW YORK, N. Y., A CORPORATION OF DELAWARE.

TYPEWRITING-MACHINE.

1,341,028.

Specification of Letters Patent. Patented May 25, 1920.

Application filed July 3, 1918. Serial No. 243,116.

To all whom it may concern:

Be it known that I, JOHN WALDHEIM, a citizen of the United States, residing in Elizabeth, in the county of Union and State 5 of New Jersey, have invented certain new and useful Improvements in Typewriting-Machines, of which the following is a specification.

My invention relates to typewriting machines of the class wherein a plurality of separate and distinct printing mechanisms or devices are provided, any one of which may be operated by a single set of key levers and from a single keyboard; so that a 15 plurality of fonts of type differing in style from one another, or fonts of type adapted for writing in two or more languages, are available for use in one and the same machine; the machine being capable of adjustment in such a way that any one of the printing mechanisms may be used according to the requirements or choice of the user of the machine.

The object of my invention is to provide 25 certain improvements in and relating to typewriting machines of the type or class above referred to, the invention to which this present application relates being an improvement upon the typewriter disclosed 30 in my co-pending application, filed March 20, 1918, Serial No. 223,489.

In the present application there is provided a plurality of printing devices, preferably in the form of type-sets, each comprising a type-segment carrying a plurality of pivotally supported type-bars, said printing devices being supported in fixed relation to each other from and by the main frame of the machine, so that the main frame and 40 the printing devices form a unitary structure; the printing mechanisms, each collectively considered, being held in fixed and unchanging relation with the main frame and with each other.

Supported by and movable relatively to the main frame of the typewriter, is a supplemental frame, which carries a set of key levers, whereby any one of the printing devices may be operated, a carriage for supporting a work-sheet to be typed upon, and means for regulating and controlling the movement of the carriage to secure a proper spacing of the characters impressed upon the work-sheet; the supplemental frame to-

gether with the key levers, the carriage, and 5 the elements concerned with the movement thereof, forming a second unitary structure movable relatively to the main frame and to the printing devices supported thereby, in order to bring a work-sheet carried by 60 the carriage into positions such that it may be typed by any one of said printing devices, and into positions such that the particular printing mechanism selected for use may be operated by the key levers. 65

The various elements and groups of elements carried by the supplemental frame are therefore held in permanent relation to one another, and move in unison relatively to the stationary printing mechanisms 70 carried by the main frame of the machine; the printing mechanisms being arranged side by side and the movement of the supplemental frame taking place in a direction parallel with the axis of a platen carried 75 by the carriage.

The supplemental frame carries escapement mechanism for regulating the movement of the carriage for letter-spacing. Suitable line-spacing mechanism for rotating the platen may also be provided, which mechanism, however, is not illustrated in detail herein. A single escapement is used, but each type-set is shown as provided with a separate universal bar, segmental in form 85 and pivotally supported from the type-bar supporting-segment thereof; the escapement mechanism being brought into position so that it may be operated by the universal bar of the particular type-set selected for use as 90 the supplemental frame is moved to bring the key levers into operative relation with the type-set in question.

The escapement mechanism is shown as operated through an intermediate reciprocating member with which the universal bar engages; and suitable ribbon-supporting and feeding mechanism may be also employed.

Motion may be transmitted from the key 100 levers to the type-bars through sets of intermediate levers operatively connected with the type-bars, a set of intermediate levers being provided for each separate type-set. The key levers are moved into operative relation with the set of intermediate levers associated with the type-bars of the type-set selected for use by moving the supple- 105

mental frame, as above explained; and suitable locking mechanism is shown as provided for locking the supplemental frame in positions to secure the proper operation of each type-set, and for releasing the same when it is desired to change to and to write with another type-set.

Other features and advantages will hereinafter appear.

10. In the accompanying drawings,

Figure 1 is a skeleton view illustrating my improved typewriting machine in perspective.

15. Fig. 2 is a staggered vertical sectional view taken near the middle of the machine and extending from the front to the rear thereof.

20. Fig. 3 is a view showing a section taken upon a plurality of horizontal planes indicated by the broken line 3 of Fig. 2.

25. Referring to the drawings, my improved typewriting machine comprises a suitable main frame shown in a conventional manner in the drawings as comprising two side members 4, the rear ends of which are connected with one another by means of a cross connecting member 5, and the front ends of which are connected by a bar 6 which also serves as a track for supporting the front 30 end of a supplemental frame, which carries the movable key levers and the work-sheet supporting and advancing mechanism of the typewriter; the cross connecting member 5 whereby the rear ends of the side members 4 are connected with one another being provided with guides 7 for guiding the rear end of the supplemental frame which supports the key levers and work-sheet supporting and advancing mechanism as said frame is 35 moved relatively to the main frame.

40. The reference numeral 8 designates the movable supplemental frame as a whole, the same comprising two side members 9, the front ends of which are connected with one another by a bar 10, and the rear ends of which are connected with a bar 11, the edges of which are provided with guides 12 located adjacent the guides 7 in the main frame of the machine, suitable balls 13 being 45 commonly interposed in order to reduce friction. Extending upwardly from the rear ends of the side members 9 of the movable frame are standards 14 which support the carriage 15 of the typewriter, the escapement mechanism for controlling the movement thereof, and other elements, as will hereinafter appear.

45. The front end of the supplemental frame is supported by the front cross bar or rail 6 above referred to, suitable rollers 16 being preferably journaled in the side members of the frame to reduce the friction between the parts. The supplemental frame, above referred to, carries and serves as a support 50 for a set of operating keys which constitute

the keyboard of the machine, for the carriage 15 whereby the platen 17 is carried, as well also as for the escapement mechanism and the mechanism for shifting the platen into its upper and lower-case positions, all of which sets of mechanisms are connected in fixed relation with one another and with the movable frame made up of the members 9, 10, and 11, and move in unison therewith. The front end of the carriage is supported 75 by a cross rail 18 extending between the side members 4 of the main frame of the machine, and the rear end of the carriage is supported by and moves along a rail 19 supported at the upper ends of the standards 80 14; the carriage being ordinarily moved by means of a spring drum operatively connected therewith, but which is not shown in the drawings.

50. The reference numerals 20 designate two separate and independent printing or typing mechanisms supported from the main frame of the machine and held in fixed relation therewith and with one another, said printing mechanisms being shown as comprising type-sets secured to and supported by a bar 21 which extends between the side members 4 of the main frame, and the ends of which are permanently secured thereto. These type-sets each comprise a type-bar supporting segment 22, which segments are secured to the cross bar 21; and 23 designates type-bars, a portion only of which is shown, said type-bars being pivotally secured at 24 within slots 25 provided in said segments. The type-bars 23 are operated to move their free ends into contact with a work-sheet extending about the platen 17 by means of bell-crank levers 26, one for each type-bar, the upper ends of said levers being operatively connected with the type-bars by a pin-and-slot connection 27. These bell-crank levers are themselves pivotally supported at 28 in a slotted bar 29 extending between and the ends of which are secured to the side members 4 of the main frame of the machine.

55. The bell-crank levers 26 are operated by means of a series of levers 30, the rear ends of which are pivotally supported at 31 in a slotted bar 32 extending between and the ends of which are connected with the side members 4 of the main frame, the front ends of said levers being guided by a slotted guide 33, the ends of which are also secured to the side members 4. The levers 30 are operatively connected with the forwardly-extending arms of the bell-crank levers 26 by pin-and-slot connections 34, from which it follows that downward movement imparted to the forward ends of the said levers will 60 operate the type-bars 23 through the bell-crank levers 26. The free ends of the type-bars 23 are supported in type-baskets 34 when in their lowermost position as shown, one such basket being provided for each 65

type-set; and guides 35 for guiding the free ends of the type-bars as they approach the printing point are also provided. It will be understood that operating levers like the 5 levers 30 are provided for each of the type-bars of each type-set, although a part only of said levers, as well as of the type-bars themselves, are shown in the drawings.

The supplemental frame 8 serves as a support for a plurality of key-levers 36, a part 10 only of which is shown, the forward ends of which levers carry keys 37, which constitute the keyboard of the machine, and the rear ends of which levers are pivotally supported on a rod 38 and in slots provided in 15 a forwardly-projecting rib upon the rear connecting bar 11 of the supplemental frame; the key-levers being guided adjacent their forward ends by a slotted guide 20 39 extending between the side members 9 of the supplemental frame.

The key-levers 36 are each provided with upwardly-extending portions 40 terminating in hooks 41, which hooks may be brought 25 into position above either set of operating levers 30, which operate the type-bars of their associated printing mechanisms or type-sets above referred to, by moving the supplemental frame to one side or the 30 other of the main frame of the machine; whereupon, and as the key-levers are depressed, the type-bars of the particular type-set selected for use may be operated. It will be appreciated that as the supplemental 35 frame is moved from side to side, the carriage 15 and platen 17 carried thereby, as well as the escapement mechanism, will move with the keyboard, as said elements are supported from the upwardly-extending 40 standards 14 which form a part of the supplemental frame and move in unison therewith, as above explained.

To lock the supplemental frame and key-levers and work-sheet supporting and advancing mechanism carried thereby in proper position so that either one of the type-sets may be operated by the single set of key-levers. I provide suitable locking mechanism; the same being shown as comprising a swinging locking pawl 42 pivotally supported in lugs 43 carried by the rear connecting bar 11, and the free end 44 of which pawl is adapted to enter either one of two slots 45 provided in the rear cross bar 5 of the main frame of the machine, said pawl being operated through a connecting link 46, the ends of which are operatively connected with said pawl and with the lower end of an arm 47 carried by a rock-shaft 48 supported in bearings provided in the side members 9 of the supplemental frame, said rock-shaft being operated by an arm 49 located at either side of the keyboard of the machine. The arm 49 is shown 60 as held in its forward position and against

a suitable stop by means of a spring 50, the effect of which is to hold the free end 44 of the pawl 42 in engagement with a slot 45. Preferably a smooth rib 51 is provided which extends between the slots 45, so that after the pawl 42 has been moved out of engagement with the slot 45 and the supplemental frame moved slightly, the free end of the pawl may be permitted to rest upon and slide along the said rib during side-wise movement of the supplemental frame; said free end snapping into the other of the slots 45 at the end of the sidewise movement referred to, due to the action of the spring 50, as will be appreciated. The side-wise movement of the supplementary frame 8 is determined by stops 45^a against which the pawl 45 strikes.

The reference numeral 52 designates rocking members, two such members being employed, although only one is shown, which members are supported by a shaft 53 supported in bearings provided upon the standards 14, and the forward ends of which members carry a shifting rail 54 through 85 which vertical movement is transmitted to the platen 17 to move it into its upper and lower-case positions; said rocking members 52 being operated by shift levers 55 carried by the supplemental frame, and which shift 90 levers transmit motion to the rocking members through upwardly-extending arms 55^a, the free ends of which engage said members, from which it will be observed that the mechanism for shifting the platen into its upper and lower-case positions is carried by and moves with the supplemental frame, and is always in position to be operated by the arms 55^a carried by said frame.

Carried by the rear connecting member 11 is a bracket 56 which serves as a support for the escapement mechanism for regulating the movement of the carriage, which mechanism, therefore, partakes of the movement of the supplemental frame 8.

The escapement or letter-feeding mechanism itself may be of any suitable form. As shown, however, said mechanism comprises fixed and movable dogs 57, 58 carried by a dog rocker 59, and which dogs are adapted to engage the teeth of an escapement wheel 60 supported by the bracket 56; said escapement wheel being geared to the carriage 15 through a pinion 61 in engagement with a rack 62 pivotally mounted on the carriage 15. The dogs 57 and 58 are operated by means of a reciprocating intermediate member 63 pivotally supported by a link 64 and arms 65 carried by a pivotally supported rocker, in order that its movements may be maintained parallel, which intermediate member is operatively associated with the dogs.

The forward end of the reciprocating member 63 is engaged and moved rear- 125 130

wardly by either one of two segmental universal bars 66 associated one with each of the type-sets 20 and lying within grooves provided in the rear sides of the segments 5 22, one of said bars being shown at 66, Fig. 2. These universal bars are supported from the rear sides of the segments in such a way that they will be maintained parallel as they move toward and from the segments, and 10 in such a way as to reduce friction to a minimum, by means of bell-crank levers 67, 68; the longer arms of which are pivotally connected with the universal bars, while the shorter arms are connected with one another through links 69, a pair of such bell-crank levers 67 being preferably provided at each end of each universal bar and one bell-crank lever 68 near the middle of said universal bar. This parallel mechanism is 15 20 not illustrated in detail in the drawings accompanying this application, as the same may be identical in construction and operation with the similar mechanism illustrated and described at length in my application 25 herein referred to.

Each universal bar is provided with a bar 70 so positioned as to engage the free end of the reciprocating members 63, from which it will be appreciated that as the supplemental frame 8 is moved from side to side of the main frame of the machine, the reciprocating member 63 will be moved therewith, and will be brought into positions adjacent one or the other of the bars 70 of 30 35 the universal bars of the two type-sets, so that motion will be transmitted to the single escapement mechanism of the machine by the universal bar of the particular type-set or printing mechanism selected for use. 40 The reciprocating member 63, in addition to being operable by the universal bars 66 as above pointed out, may also be operated through a depending arm 71 of the rocker which carries the arm 65, said arm 71 being 45 50 engaged by a finger 72 with which the space-bar 73 of the keyboard is operatively connected, to thereby provide for spacing the carriage between words or independently of the type-sets. The connections intermediate the space-bar and the reciprocating member 63 comprise a lever 73^a pivotally supported on the rod 38.

The end portions 4 of the main frame of the machine should permit the ends of the 55 connecting bar 11 to move beyond them, to which end they are shown as provided with openings 74 so located, and of such a size that the ends of the connecting bar of the supplemental frame may extend there-through when said frame is in either one of its extreme positions, as shown in Fig. 3. This feature provides for a reduction in width of the main frame of the machine, and necessitates the use of a main frame of 60 65 a width no greater than one corresponding

approximately with double the width of the supplemental frame and keyboard of the machine.

Variations may be resorted to within the scope of the invention, and portions of the 70 improvements may be used without others.

Having thus described my invention, I claim:

1. In a typewriter of the class described, a main frame; a plurality of printing devices carried by said main frame and secured in fixed relation thereto and to one another; a supplemental frame carrying a set of key-levers, and work-sheet supporting and advancing mechanism, the two (said 8 key-levers and said mechanism) being connected together in fixed relation with one another and adapted to move in unison to bring a work-sheet into positions such that it may be typed upon by any one of said 8 printing devices; and means whereby said set of key-levers may be operatively connected with the particular printing device selected for use.

2. In a typewriter of the class described, 9 a main frame; a plurality of type-sets carried by said main frame and secured in fixed relation thereto and to one another, and each of which comprises a plurality of pivotally-supported type-bars and means for 9 operating the same; a supplemental frame carrying a set of key-levers, and work-sheet supporting and advancing mechanism, the two being connected together in fixed relation with one another and adapted to move 1 in unison to bring a work-sheet into positions such that it may be typed upon by any one of said type-sets; and means whereby said set of key-levers may be operatively connected with the particular type-set 1 selected for use.

3. In a typewriter of the class described, a main frame; a plurality of type-sets carried by said main frame and secured in fixed relation thereto and to one another, and each 1 of which comprises a plurality of pivotally supported type-bars and means for operating the same; a supplemental frame carrying a set of key-levers, and work-sheet supporting and advancing mechanism, the two 1 being connected together in fixed relation with one another and adapted to move in unison to bring a work-sheet into positions such that it may be typed upon by any one of said type-sets; a plurality of sets of operating levers operatively associated one set with each type-set; and means whereby said set of key-levers may be operatively connected with the set of operating levers associated with the particular type-set selected 1 for use.

4. In a typewriter of the class described, a main frame; a plurality of printing devices carried by said main frame and secured in fixed relation thereto and to one 1

- another; a supplemental frame movable in guides carried by said main frame, and which supplemental frame carries a set of key-levers, and work-sheet supporting and advancing mechanism, the two being connected together in fixed relation with one another and adapted to move in unison to bring a work-sheet into positions such that it may be typed upon by any one of said printing devices; means whereby said set of key-levers may be operatively connected with the particular printing device selected for use; a pivotally supported locking pawl carried by said supplemental frame and adapted to engage slots provided in said main frame and spaced apart from one another, to thereby lock said supplemental frame and main frame together; and means carried by said supplemental frame for operating said locking pawl.
5. In a typewriter of the class described, a main frame; a plurality of printing devices carried by said main frame and secured in fixed relation thereto and to one another; a supplemental frame movable relatively to said main frame and carrying a set of key-levers, said supplemental frame also including a carriage having a platen, and escapement mechanism for controlling the movement of said carriage; means for locking said supplemental frame and main frame together in positions such that a work-sheet carried by said carriage may be typed upon by any one of said printing devices; and means whereby the movement of said carriage is controlled by the particular printing device selected for use.
6. In a typewriter of the class described, a main frame having two guides spaced apart from one another; a bar carried by said main frame; a plurality of type-sets secured to said bar and arranged side by side, and each of which comprises a plurality of pivotally supported type-bars and means for operating the same; a supplemental frame movable relatively to said main frame and guided by said guides, and which supplemental frame carries a set of key-levers and work-sheet supporting and advancing mechanism, the two being connected together in fixed relation with one another and adapted to move in unison to bring a work-sheet into positions such that it may be typed upon by any one of said type-sets; and means whereby said set of key-levers may be operatively connected with the particular type-set selected for use.
7. In a typewriting machine of the class described, a main frame; a plurality of printing devices carried by said main frame and secured in fixed relation thereto and to one another; a supplemental frame movable relatively to said main frame; means for guiding said supplemental frame in its movements; a set of key-levers carried by said supplemental frame and movable therewith into operative relation with each of said printing devices; a carriage carried by said supplemental frame and movable therewith to bring a platen carried thereby into operative relation with each of said printing devices; a single escapement mechanism carried by said supplemental frame and adapted to control the movement of said carriage; a plurality of universal bars, one associated with each of said printing devices; means whereby said escapement mechanism may be operated by any one of said universal bars; and means whereby said key-levers may be operatively connected with the particular printing device selected for use.
8. In a typewriting machine of the class described, a main frame; a plurality of printing devices carried by said main frame and secured in fixed position relatively thereto and to one another; a supplemental frame movable relatively to said main frame; means for guiding said supplemental frame in its movements; a set of key-levers carried by said supplemental frame and movable therewith into operative relation with each of said printing devices; a carriage carried by said supplemental frame and movable therewith to bring a platen carried thereby into operative relation with each of said printing devices; a single escapement mechanism carried by said supplemental frame and adapted to control the movement of said carriage; a plurality of universal bars, one associated with each of said printing devices; means whereby said escapement mechanism may be operated by any one of said universal bars; and means whereby said key-levers may be operatively connected with the particular printing device selected for use.
9. In a typewriting machine of the class described, a main frame; a plurality of printing devices carried by said main frame and secured in fixed position relatively thereto and to one another; a supplemental frame movable relatively to said main frame; means for guiding said supplemental frame in its movements; a set of key-levers carried by said supplemental frame and movable therewith into operative relation with each of said printing devices; a carriage carried by said supplemental frame and movable therewith to bring a platen carried thereby into operative relation with each of said printing devices; a single escapement mechanism carried by said supplemental frame and adapted to control the movement of said carriage; means whereby said escapement mechanism may be operated from any one of said printing devices; a plurality of sets of auxiliary levers pivotally supported from said main frame and associated one set with each of said printing devices; and arms carried by said key-levers and adapted to be moved into opera-

80

tive relation with the set of auxiliary levers associated with the particular printing device selected for use.

10. In a typewriting machine of the class described, a main frame; a plurality of type sets carried by said main frame and secured in fixed position relatively thereto and to one another, and each of which comprises a plurality of pivotally supported type-bars; a supplemental frame movable relatively to said main frame; means for guiding said supplemental frame in its movements; a set of key-levers carried by said supplemental frame and movable therewith into operative relation with each of said type-sets; a single escapement mechanism carried by said supplemental frame and adapted to control the movement of said carriage; a plurality of universal bars, one associated with each of said type-sets; a reciprocating member adapted to be engaged by any one of said universal bars, and through which said escapement mechanism may be operated; a plurality of sets of auxiliary levers pivotally supported from said main frame, one set of said levers being associated with each of said type-sets and operatively connected with the type-bars thereof; and arms carried by said key-levers and adapted to be moved into operative relation with the set of auxiliary levers associated with the particular type-set selected for use.

11. In a typewriting machine of the class described, a main frame having two guides spaced apart from one another; a plurality of printing devices carried by said main frame and secured in fixed position relatively thereto and to one another; a supplemental frame movable relatively to said main frame and guided in its movements by said guides; a set of key-levers carried by said supplemental frame and movable therewith into operative relation with each of said printing devices; a carriage carried by said supplemental frame and movable therewith to bring a platen carried thereby into operative relation with each of said printing devices; a single escapement mechanism carried by said supplemental frame and adapted to control the movement of said carriage; means whereby said escapement mechanism may be operated from any one of said printing devices; and means whereby said key-levers may be operatively connected with the particular printing device selected for use.

12. In a typewriting machine of the class described, a main frame having two guides spaced apart from one another and located one at the rear and the other at the front end thereof; a plurality of printing devices

carried by said main frame and arranged side by side, said printing devices being secured in fixed position relatively to said main frame and to one another; a supplemental frame movable relatively to said main frame and guided in its movements by said guides; a set of key-levers carried by said supplemental frame and movable therewith into operative relation with each of said printing devices; a carriage carried by said supplemental frame and movable therewith to bring a platen carried thereby into operative relation with each of said printing devices; a single escapement mechanism carried by said supplemental frame and adapted to control the movement of said carriage; means whereby said escapement mechanism may be operated from any one of said printing devices; and means whereby said key-levers may be operatively connected with the particular printing device selected for use.

13. The combination with a platen, of a plurality of type-sets, a single set of type keys, a frame supporting said keys and said platen and adapted to permit the platen to travel thereon, and means for moving said frame to render said keys effective with any one of said type-sets to print upon the platen.

14. The combination with a platen, of a plurality of type-sets, a single set of keys, a frame supporting said keys, means for moving said frame to render said keys effective with any one of said type-sets, and a carriage for said platen supported for letter-feeding movements on said frame and connected to be moved with said frame.

15. The combination with a platen, of a plurality of type-sets, a single set of keys, a frame supporting said keys, means for moving said frame to render said keys effective with any one of said type-sets, a carriage for said platen, said carriage being supported for letter-feeding movements on said frame and adapted to be moved with said frame, and a carriage-escapement on said frame, and adapted to be moved therewith, so as not to disturb the relation between said carriage and said escapement when said keys are moved from one type-set to another.

16. The combination with a platen, of a plurality of type-sets arranged adjacent to each other, a single set of keys, a movable frame supporting said keys and said platen said frame being adapted to be moved to bring the said keys into coöperative relation with any one of said type-sets, means for stopping said frame in the proper position relatively to said type-sets, and means to maintain said frame in fixed relation with any one of said type-sets.

17. In a typewriting machine, the combination of a fixed unit and a movable unit;

- said fixed unit comprising a plurality of type-sets; said movable unit comprising a single set of keys, a platen, a carriage for said platen, feeding mechanism for said carriage, and case-shifting mechanism; the keys of said movable unit being adapted to be brought into relation with any one of said type-sets; and means for maintaining a fixed relation between said units.
- 10 18. In a typewriting machine, the combination with a platen, of a plurality of type-sets arranged side by side, means for actuating said type-sets individually, a carriage for said platen, letter-feeding mechanism for said carriage, means supporting said platen to enable it to move from one type-set to another and connections in said supporting means adapted to maintain the relation between said carriage and said feeding mechanism when so moved.
- 15 19. The combination with a platen, of a plurality of type-sets, a single set of type-keys, a frame supporting said keys and said platen and adapted to permit the platen to travel thereon, means for moving said frame to render said keys effective with any one of said type-sets to print upon the platen, a case-shift rail for the platen forming part of the frame and moving therewith, and 20 case-shift keys moving with the frame and adapted to operate said rail.
- 20 20. The combination with a platen, of a plurality of type-sets, a single set of type-keys, a frame supporting said keys and said platen and adapted to permit the platen to travel thereon, means for moving said frame to render said keys effective with any one of said type-sets to print upon the platen, a case-shift rail for the platen forming part of the frame and moving therewith, and 25 case-shift keys moving with the frame and adapted to operate said rail.
- 25 21. In a typewriting machine, the combination with a main frame, of a carriage comprising a platen, a secondary frame in which said carriage is adapted to travel, 30 rails in the main frame upon which the secondary frame is adapted to travel, a rail in the secondary frame upon which the carriage is adapted to travel, a rail in the main frame upon which the carriage is adapted to travel, and an escapement mechanism for the carriage in the secondary frame.
- 30 22. The combination with a platen, of a plurality of sets of type-bars, a single set of keys, a carriage for the platen, a universal 35 bar for each set of type-bars, a single escapement device for the carriage, comprising a reciprocating member, a main frame, and a secondary frame carrying said keys, said platen, and said escapement device, and 40 adapted to be arrested to enable either of said type-bar sets to print upon the letter-space at which the platen is held by the escapement device, and bringing the corresponding universal bar adjacent the escapement reciprocating member to actuate the 45 escapement device.

JOHN WALDHEIM.
